UNITED STATES PATENT OFFICE.

JOHN L. MONTEN AND CARL NELSON, OF CHICAGO, ILLINOIS.

CLAMP AND LOCKING DEVICE FOR FORMS FOR CONCRETE CONSTRUCTION.

Application filed July 10, 1922. Serial No. 574,116.

To all whom it may concern:

Be it known that we, JOHN L. MONTEN and CARL NELSON, former subjects of the King of Sweden, (we have declared our intentions of becoming citizens of the United States), residing at Chicago, in the county of Cook and State of Illinois, have invented certain new and useful Improvements in Clamping and Locking Devices for Forms for Concrete Construction, of which the following is a full, clear, concise, and exact description, reference being had to the accompanying drawings, forming a part of this specification.

15 Our invention relates to improvements in clamps and locking devices for forms for concrete construction designed for use especially in the formation of wall copings, belt courses on building structures, window 20 sills, door sills and watertables for building foundation and like structures.

One object of our invention is the production of a device of this character which may be readily and quickly erected for use 25 and as readily and easily removed after setting of the concrete for further use. A further object is the provision of a device of this character which will be of an adjustable nature permitting of ready and 30 expeditious adjustment to meet various conditions and requirements, and which will be firm and rigid after application or assembly so as to insure the production of a concrete structure which will be of accurate design 35 and finished appearance.

A still further object is the production 40 of a device for concrete construction which will be of durable and economical construction and highly efficient in use. Other objects will appear hereinafter. With this object in view the invention consists in the combinations and arrangements of parts hereinafter described and claimed. The invention will be best understood by reference to the accompanying drawings wherein like numerals refer to corresponding parts.

Fig. 1 is a plan view showing a form for 50 making a wall coping.

Fig. 2 is a cross section including a brick wall portion.

Fig. 3 is a side elevation of Fig. 1.

Fig. 4 shows three different sides of the clamp.

55 Fig. 5 is an end view of our form, a section of wall and of a molded sill,

Fig. 6 is a top plan view of Fig. 5.

In the several views 19 represents the body of our improved form. Its construction and formations are particularly adapted for sheet metal material, which is light, easily and with comparative cheapness stamped with ornamental surface designs, does not adhere to the molded structure like wooden molds, is more durable, etc., as will appear from the hereinafter detailed description. Said body 19 is strengthened against bending strains by bent out edge portions, such as an upper edge flange 4 which is bent outwardly from the wall-side 70 of the form, an inward horizontal bend 4' and a flange 8 extending from the flange 4' and forming a stop which is designed to bear against the side of the wall —9—, as shown most clearly in Figures 2 and 5. 75

As shown in the cut-away portions 32 in Figure 3, portions of the stop or gauge flange 8 are struck out therefrom at right angles to form supporting feet, lips, ears, lugs, or rests adapted to rest on top of the structure 9 upon which the molded structure is placed. These feet or supports —31— being thin, or merely the thickness of the sheet metal, are easily withdrawn when the plastic material has "set," and leave no appreciable 85 marks, scars or recesses that require separate attention after removal of the form. Along its lower edge the form body 19 is strengthened longitudinally by substantially two "angle-irons," or the right angle bend that 90 forms the rib or flange 4' and the right angle final bend which provides the stop-plate 8, and these features are retained in the form in its different applications, and whether doubly, as in Figure 2, or singly, as in Figures 5 and 6. 95

Provision for joining together a plurality of bodies 19 to form longer units of mold-structure, is made in the form of vertical end flanges, or bent out portions, 10 which 100 are adapted to engage a slot 14 in a forked clamp-member 5, as indicated at 10 and 14 in Figure 3. The flanges 10 are held against accidental displacement from the slot 14 in a lateral direction, by a slot 14' arranged at 105 right angles to the slot 14 and formed between an enlarged portion 6 of the clamp member 5 and the forked portion containing the slot 14, (as shown on an enlarged scale in Figure 4), said slot 14' being engaged by upwardly projecting lugs 6 which 110 are left as unbent portions of the upper edge

of the body 19 after the rib or flange 4 has been formed. At the upper end of the forked portion —22— of the clamp-member 5 the latter has a screw-threaded bore that 5 is engaged by a screw 13, which, as shown in the middle view in Figure 4, and on a smaller scale in Figures 2 and 5, may be brought to bear against the lugs 6, or clamp the latter in the slot 14'.

10 When the clamp member 5 is employed in forming belt courses, window sills, water tables crowning foundations, and the like, a useful adaptation of the invention that is suggested by Figures 5 and 6, said clamp 5 by being placed in a horizontal position and having its slot 14' engaged with the stiffening rib 4 instead of with the lugs 6, as in Figs. 1, 2 and 3, serves to support a temporary end-wall 18 in any position along 15 the body 19 by clamping the screw 13 against said stiffening flange 4, the plate, or end wall 18 being either placed against the forked portion of the clamp member or inserted in the slot 14. When the end wall 18 fits the slot 14 the flat sides of the slot 14 will hold it very firmly against accidental lateral displacement of its lower end by the 20 moderate pressure of the plastic material 20. In Fig. 5 the dotted lines 23 represent the bottom of the usual wood-work frame which may be in position either before or after the concrete has been poured in.

Provision is made for supporting parallel or spaced apart mold sides 19 by connecting 35 their clamp-members 5 through a cross-bar, or a plurality thereof. Said cross-bar —11— has its respective ends mounted in openings 12 transversely to which are screw-bores engaged by screws 2 which are tightened against the bar 11 after it has been adjusted to hold the sides or forms in their desired relation to each other to form a structure or molded form 7 as indicated in Figures 1 and 2.

45 The different flange engagements of the clamp member and the flanges on the form-body 19, suggested by comparing the vertical with the horizontal clamp member 5 in, for instance, Figures 5 and 6, and the additional uses of the slot 14 also suggested in said figure are susceptible of many adjustments and arrangements that obviate the additional elements that must be provided for older forms of mold structures which are 50 adapted for only one kind of structure and must be provided with a variety of auxiliary members.

We claim as our invention:

1. A mold wall or form having bent out 60 edge portions which form stiffening ribs or flanges longitudinally of said wall or form, and laterally stiffening end flanges, clamp-members which slidably embrace the opposite sides of said end flanges and couple them together, and lateral supporting means be-

yond the molding space for said clamp-members.

2. A mold comprising a form having its opposite edge portions bent out in opposite directions and forming longitudinal 70 strengthening ribs, said form having similar bent out vertical edge portions which form lateral stiffening ribs, and means which reinforce and couple together abutting lateral stiffening ribs to lengthen the mold- 75 form.

3. A mold-form having integral bent portions forming longitudinal and lateral stiffening ribs, and forked members which clamp together and reinforce the lateral 80 stiffening ribs on abutting forms.

4. A mold comprising a form with integral bent portions which form horizontal and vertical stiffening ribs and a stop-flange to engage a wall-structure, and arranged to form a projecting ledge, and feet or supports struck out of the bottom edge 85 of the latter to support said form.

5. A mold-form having an upper angle flange and lower double angle flanges which 90 form a wall-engaging stop and a ledge projecting said mold-form beyond the vertical plane of a wall, integral struck-out supporting feet which extend from said double angle flanges at the bottom edge of 95 the mold, and integral end flanges on said mold to be clamped to similar end flanges on adjacent mold-forms.

6. A mold-form which comprises a wall-body with integral and laterally projecting 100 horizontal and vertical stiffening ribs and integral supporting feet which project from the bottom of the mold-form, means projecting said mold-form beyond the vertical plane of a wall, and means supporting a plurality of such forms in space-apart relation as walls for opposite sides of a 105 molded structure.

7. A mold-form with laterally bent out 110 horizontal stiffening flanges, and similarly bent out vertical flanges, in combination with a slotted clamp which is slidable over the upper ends of said vertical flanges to support an auxiliary end-wall extending at right angles to said form and support a 115 plurality of said forms in end-to-end alignment.

8. A mold which comprises a plurality 120 of forms the end of which meet, outwardly bent flanges on said forms to overlie each other, and a slotted clamp which straddles the abutting ends of adjacent forms and binds said ends together.

9. A metal wall mold with laterally bent 125 end-flanges, means reinforcing and embracing said end-flanges and detachably connecting a plurality thereof to extend the length of said wall, a connecting-bar for said reinforcing means, and means for securing it to said mold-wall.

10. A mold form which comprises a form unit provided with upwardly projecting lugs, means for coupling together said lugs, means for holding said unit in spaced apart 5 relation to a similar unit, a bar, a slotted and apertured block adjustably mounted on said bar and engageable with said lugs, and a clamp on said block adapted to engage said unit.
- 10 11. A metal form having bent out edges which form stiffening ribs, a locking device for a plurality of such forms, said locking device consisting of a slotted block to engage the stiffening ribs of adjacent forms, 15 said block having a transverse opening therethrough to be engaged by the end of a cross-bar, and a screw in said block to engage and hold said end against movement relative to said block.
- 20 12. A mold form for concrete construction which comprises form units having laterally projecting end-flanges, fingers or lugs which extend from the bottom edges of said units, clamps holding a plurality of 25 said units in alinement, and bars engaged by said clamps to hold parallel forms in spaced apart and alined relation.
13. A mold form comprising a metal unit with laterally projecting bent out edge portions which form thin and integral fingers 30
- that extend from the bottom edges of the form and support said form on a wall but adapted to be withdrawn after the molded form has set or hardened without leaving a disfiguring opening or scar in said form. 35
14. A supporting clamp for mold-forms which comprises a slotted block designed to occupy a horizontal position, and having a recess therein arranged at right angles to the slot in said block, said block being arranged to engage an upper flange of a form unit, and a screw in said recess adapted to be clamped against said flange. 40
15. The combination with form units, of vertical lugs on the ends thereof and flanges, 45 a slotted block constructed to engage abutting flanges of adjacent units, and a clamp in said block arranged to clamp together said lugs.
16. A mold form and supports therefor, 50 which comprises form units, a slotted block which straddles and is vertically supported by said units and coupling them together, and means holding said units in alinement and in spaced apart parallel relation. 55

In witness whereof, we have hereunto subscribed our names.

JOHN L. MONTEN.
CARL NELSON.
